UNITED STATES PATENT OFFICE

170,519

SHOEHORN

Gerard Beroiset, Toledo, Ohio

Application April 27, 1953, Serial No. 24,706

Term of patent 14 years

(Cl. D86—10)

To all whom it may concern:

Be it known that I, Gerard Beroiset, a citizen of the United States and a resident of Toledo, Lucas County, Ohio, have invented a new, original and ornamental Design for a Shoe Horn, of which the following is a specification, reference being had to the accompanying drawing forming a part thereof.

In the drawing:

Figure 1 is a front elevation of the shoe horn, showing my new design;

Figure 2 is an edge elevation of the shoe horn;

Figure 3 is a rear elevation of the shoe horn;

Figure 4 is an enlarged transverse sectional view on the line 4—4 of Figure 1; and

Figure 5 is an enlarged transverse sectional view on the line 5—5 of Figure 1.

I claim:

The ornamental design for a shoe horn, as shown.

GERARD BEROSET.
